MOLDING MACHINE

Hans Stemmler and Karl Künzi, Schaffhouse, Switzerland, assignors to Aktiengesellschaft der Eisen- und Stahlwerke vormals Georg Fischer, Schaffhouse, Switzerland

Application August 4, 1942, Serial No. 453,586
In Switzerland November 24, 1941

1 Claim. (Cl. 18—16)

This invention relates to molding machines comprising mold lifting pins which are arranged on a vertically displaceable supporting frame and are controllable from a single control position, each lifting pin being adapted to be forced against the underside of the casting box from below independently of the other pins. This arrangement is intended to serve the purpose of initiating the rising movement of all the lifting pins at the same time so that the casting box is maintained parallel with its initial position during the whole lifting operation.

Adjusting devices for the lifting pins of molding machines that are controllable from a single control position have already been proposed. Some of these propositions relate to arrangements with pistons which can be hydraulically or pneumatically actuated and the piston rod of which constitutes a lifting pin of itself. If the pressure fluid conduits that are associated with such lifting pins of an individual molding machine are led to a single valve, common control of the pins is feasible. This arrangement has, however, not withstood the test of actual practice for the reason that, when the resistance opposed to the lifting operation varies, the pistons fail to rise at uniform speed so that the casting box is likely to assume an inclined position even from the start of the lifting whereby the mold is liable to be detrimentally affected.

Other known proposals provide for lifting pins which are mounted on rotatable crank discs serving as cam discs. Said discs are rotated by means of press bolts that are operated from a single control position. The throw of such crank discs is restricted and is by all means smaller than required for die carrier plates presently used, the thickness of which averages about 100 millimeters. Due to this fact the applicability of crank discs is subject to the requirement of compensating deficiency in length of throw in adaptation to excess thickness of the die carrier plates used, by applying exchangeable shimming blocks of different thicknesses to the lifting pins.

In contradistinction thereto the arrangement according to the present invention is simplified in that at least part of the lifting pins, each consist of two telescopically connected extensible and fixable parts that are all spring biased in the upward direction, one of said parts of each pin being locked in a different position of height relative to the supporting frame at the end of travel of its associated spring means.

This arrangement does away with shimming blocks for the lifting pins. Each of the extensible

5 lifting pins, which has readily been preliminarily adjusted by hand to the thickness of die carrier plate required, further automatically adjusts itself to any uneven portion of the underside of the casting box that may be present and all the lifting pins are locked in rigid relation to the supporting frame at the moment of beginning of the lifting so that all parts of the casting box share in the movements of the supporting frame simultaneously.

10 Various embodiments of the molding machine according to the present invention are illustrated by way of example only in the accompanying drawings, in which

15 Fig. 1 is a view of an assembled molding machine according to the invention inclusive of the lifting pins;

Fig. 2 is a part-view of a slightly modified embodiment of the invention compared to that shown in Fig. 1;

20 Fig. 3 is a longitudinal section of a lifting pin;

Fig. 4 is a longitudinal section of a modified lifting pin;

25 Fig. 5 shows a detail of the clamping ring of Fig. 4;

Fig. 6 shows a cross section of a lifting pin, and

Fig. 7 shows a longitudinal section of a further modified lifting pin.

30 In Fig. 1, the outer forms of the machine standard 1, and of the laterally rockable adjustable head piece 2 including a press plate 3 and a spindle 4 are illustrated. The base 5 provides the mounting and the cylinder for the press plunger

35 6 carrying the molding plate 7. On top of the die carrier plate 8 the casting box 9 comprising brackets 10 is placed. Lifting pins 11 supported by adjustable pivotal members 12 bear against the lower surface of the brackets 10. The pivotal

40 members 12 are firmly clamped to a supporting frame in pairs on either side of the molding machine by means of a screw 13 for each pair. The supporting frame 14 is firmly connected to a lifting plunger 15 interiorly of the machine standard 1.

45 The lower end of the lifting plunger 15 projects into a cylinder 16. The pressure fluid is forced into the cylinder 16, by means of a supply conduit 17, whereby the plunger 15 is raised. An upper bearing 18 guides the plunger 15 and the supporting frame 14 connected thereto in conjunction with a stuffing box 19. On the backside of the supporting frame an ear 20 is arranged in which a screw spindle 21 carrying a hand-wheel 22 is mounted. The screw spindle 21 bears

against an abutment 23 on the machine standard 1, thereby forming an adjustable, lower limiting means for the travel of the supporting frame. Supply conduits 24 lead to the lifting pins 11 via a check member 25, the conduits being connected with the same source of pressure fluid as conduit 17.

The lifting operation is carried into effect as follows:

On the completion of the compression the molding plate 1 is lowered into position corresponding to the initial position of the press plunger 6 together with the die resting thereon and the mold. The spring biased lifting pins contact with the bottom of the casting box already in their initial positions. If the operator then actuates the plunger 15 by means of pressure fluid, the fluid is also supplied to the conduits 24 and the locking plungers of the lifting pins 11. The locking plungers of the lifting pins immediately effect rigidity of connection between the supporting frame 14 and the lifting pins 11, thereby transmitting the lifting effect of the plunger 15 to the casting box. Due to the fact that the lifting pins 11 have entered into contact with the casting box by action of the springs associated therewith prior to the locking having become effective the casting box is raised by simultaneous action of all the lifting pins as soon as the pressure fluid is projected onto the locking plungers. It will be seen that by this means the absolute necessity for lifting the casting box exactly parallel to its initial position is complied with and thus the risk of injuring the mold is eliminated in that even very slight deviations from true parallelism might damage the mold.

The embodiment shown in Fig. 2 is somewhat modified from that shown in Fig. 1 and differs from the latter as regards the manner in which the previously described lifting operation is carried out. The lifting pins 28 are connected to the supporting frame 29 and are each provided with a locking device actuated by means of pressure fluid also in this case. The supporting frame 29 is guided by means of bolts 30 which are firmly secured to a press plunger 31. A collar 32 provides a lower limiting means for the travel of the supporting frame. In a bearing 33 supporting levers 34 are mounted which are firmly urged against the arms of the supporting frame 29 in automatic manner by an elastic means. In lifting the press plunger 31 the supporting frame 29 is raised together with the lifting pins 28 by the bolt 30.

Adjacent to the highest position fingers provided on the supporting levers 34 engage under the arms of the supporting frame 29 by snap action and remain in these positions until the compression is completed. In the meantime the locking effect of the lifting pins 28 is initiated by means of pressure fluid via a check member 35 and supply conduits 36. During the subsequent lowering of the press plunger 31 the arms of the supporting frame 29 abut against the supporting levers 34, so as to firmly sustain the casting box in this position. The die, together with the press piston 31 moves toward the initial position in which way the separation of the mold from the die is accomplished, so that the casting box can be removed. In the course of the subsequent joining of the die with a fresh casting box the supporting levers 34 are disengaged again by means of a handle 37, as exemplified in the drawing. Alternatively, the supporting levers

may be reset by means of pressure fluid, or other means such as an elastic tension device.

The longitudinal section of a lifting pin drawn to a larger scale in Fig. 3 shows by way of example the body 40 of the lifting pin to be integral with a pivotal member 41. The extensible part of the lifting pin consists in a tube 42 having a pointed bearing end 43 having a press-fit with the tube 42. A screw spindle 44 is firmly connected with the tube 42 by means of a plug 45. A knurled adjusting nut 46 is carried by the screw spindle 44 and is connected to a sleeve 47. The sleeve 47 carries a ring 48 which transmits the pressure of a spring 49 to the adjusting nut 46. The lower end of the spring 49 bears on a closure plug 50.

The adjustment of the lifting pin into initial position is effected by rotation of the adjusting nut 46 until the required height is reached. In this modified lifting pin arrangement provision is made for the pointed bearing ends to project somewhat above operative position when the pin is in initial position. By this means firm contact is ensured between the lifting pins and casting box portions or heels that do not extend down to the bottom of the casting box or the top of the die carrier plate. In placing the casting box in position the lifting pin portion 42, 43 is depressed together with the parts 46, 47, 48 and 49 until the underside of the casting box bears on the die carrier plate. The travel which the spring 49 performs while the lifting pin portion 42, 43 is depressed is always commensurate with the extent to which the point 43 of the lifting pin projects in the initial position above the top of the die carrier plate. As the casting box bears on the die carrier plate the lifting pins have arrived in their operating positions.

The locking means of the lifting pin shown in Fig. 3 consists in a braking block 51 which is actuated by fluid pressure and adapted to bear against the lifting pin. The pressure fluid enters through a pipe connection 52 for acting upon the unobstructed surface of a diaphragm 53. This diaphragm is forced against the braking block 51 whereby the spring 54 is compressed. In the compressed condition of the spring 54 the braking block 51 bears against the lifting pin, that is, the tube 42, thus preventing said pin from any further shifting movement within the body 40. As the pressure on the diaphragm 53 is removed the spring 54 resets the braking block 51 so as to clear the tube 42.

A similar form of lifting pin is shown in Fig. 4. The pivotal member 55 is, for example, integral with the body 56 of the lifting pin also in this case. The body 56 forms a guide for the extensible part of the lifting pin which consists in a tube 57 and a pointed bearing end 58. The bearing point 58 is in the form of a cross-cutting chisel permitting dust and sand to slide off therefrom so that the bearing surface remains permanently clean. The locking means of this arrangement consists in a braking piece 59, a diaphragm 61 and a pipe connection 62 for the pressure fluid. Compression springs 60 tend to press the braking piece into unlocking position. Instead of the spring 47 in Fig. 3 a spring 63 as per Fig. 4 is provided which is however effective only for a lift of short length. This length is so chosen in this instance as to suffice, when the tube 57 is adjusted into a certain position, for compensating any difference of form of various kinds of casting boxes that are likely to enter into the question. To this end a spring housing 64 with a clamping ring 65

inserted therein must be displaced relative to the tube 57 as soon as a different die carrier plate or a different kind of casting box is employed. For this purpose the pressure exerted by the clamping ring 65 is so adjusted by means of an adjusting screw 66, a spring 67 and a press ring 68 that the tube 57 slides along the sleeve 64 if any tension or compression to which the tube 57 is subjected exceeds the effort of the spring 63. A stop 69 and a screw cap 68' are provided for the purpose of retaining the sleeve 64 if the tube 57 is subjected to tension. By this means the lifting pin can be adjusted by one hand only.

Fig. 5 shows a development of a specific form of the clamping ring 65.

A construction producing a double clamping effect is illustrated in cross section in Fig. 6. A pivotal member 70 forming an integral casting with the half 71 of the body incloses the locking elements in conjunction with a casing 72. A tube 73 is gripped on opposite sides by the cooperating locking elements 74 and 75 which elements are forced asunder to some extent by springs 76 in their initial positions. The locking element 74 is screwed together with the inlet pipe connection 77 so as to form a self-contained unit, a diaphragm 78 being interposed between said two parts. To the side of the diaphragm 78 remote from the pressure fluid a press piece 79 is fastened which transmits the deflection of the diaphragm to the locking element 75. As the pressure fluid enters the pressure chamber 80 compression forces acting on one hand on the locking element 75 through the press piece 79 and on other on the inlet pipe connection 77 are set up which connection transmits said forces to the locking element 74. After the springs 76 are overpowered the tube 73 is locked to the pivotal member 70 by an effect similar to that produced by a pair of pincers.

A further form of lifting pin is shown in cross section in Fig. 7 in which the pressure effect exerted by the entering pressure fluid is transmitted

to the locking means by means of a leverage. In the instance shown the numeral 81 refers to the body of the pivotal member which joins with a guide member 82 for a tube 83 of the lifting pin.

5 A cylinder 84 containing a piston 85 is secured to the underside of the pivotal member 81. The pressure fluid entering the pressure chamber 86 has the effect to compress a spring 87 by means of the piston 85, whereby the piston rod 88 is shifted in the direction toward the tube 83. In consequence thereof, a lever 89 to which the rod 88 is pivotally connected turns about a pin 90, thereby pressing the locking means 91 against the tube 83. As the pressure fluid is discharged from the pressure chamber 86 again the spring 87 which bears against an annular abutment 92 shifts the piston 85 back into initial position. The rod 88, the lever 89 and the locking means 91 return together with the piston 85 into initial position.

10 15 20 We claim:

In a fluid pressure operated machine for forming molds in combination, a casting box, a press plate, a die carrier member located beneath said casting box, the die carrier member having die portions to be contacted by work material, a vertically displaceable supporting frame, a fluid actuated press motor for vertically displacing said frame, lifting pins for said casting box carried by said supporting frame and each comprising two 25 30 35 40 telescopically connected, relatively shiftable, and fixable parts, spring means for biasing at least one of said shiftable parts upwardly into contact with the casting box before actuation of the press motor, a braking motor intercalated between each pair of telescopically connected lifting pin parts, a source of pressure fluid, and means connecting the fluid press motor and also the braking means with said source of fluid pressure, the lifting pins thus being locked in their respective positions 40 contacting the casting box at different heights relative to the supporting frame.

HANS STEMMLER.

KARL KÜNZI.
